ARTICLE OF FURNITURE

Arthur B. Modine, Racine, Wis., assignor to
 Modine Manufacturing Company, Racine,
 Wis., a corporation of Wisconsin

Application October 24, 1932, Serial No. 639,319

13 Claims. (Cl. 62—131)

The invention relates to air conditioning devices and primarily to that type which is designed to cool air and deliver said air in a cooled condition to a room in which the device is located.

5 6 The invention particularly relates to the production of a piece of furniture such as for instance a table having means for circulating air and directing said air toward the occupants of the table.

10 10 It is also an object of the invention to provide a piece of furniture having means for circulating and means for cooling air, the cooling agent and the air advancing means being located in one of the elements of the table, the other element

15 15 such as the top having means through which air is discharged and delivered in a plane at one side of said top and toward an edge thereof.

In addition to the above, it is an object to provide a device of this character with means

20 20 for regulating the discharge of air therefrom to thereby allow an occupant of the table to regulate the degree or amount of air circulating in his direction.

25 25 The invention has an additional object the provision of means whereby the cooling agent or a container therefor is removably arranged in the device to facilitate replacement of the device when this becomes necessary or desirable.

30 30 The invention has these and other objects, all of which will be explained in detail and more readily understood when read in conjunction with the accompanying drawings which disclose various arrangements which may be resorted to in order to accomplish the invention, it being 35 therefore obvious that other changes may be employed without departing from the spirit of the appended claims forming a part hereof.

In the drawings, Fig. 1 is a central longitudinal section of a construction forming a table having means combined therewith for accomplishing desired advantages.

40 Fig. 2 is a fragmentary sectional view of a modified arrangement which may be resorted to;

45 Figs. 3 and 4 are also sectional views of a portion of a table structure capable of functioning to produce the various advantages hereinabove referred to; and

50 Fig. 5 is an elevation of a cooling agent which may be employed with other elements of the structure to accomplish the cooling of air.

The article of furniture illustrated in Fig. 1 involves the use of a member 10 and an element 11. The member 10 functions to support the element 11 and the two cooperate with each other 55 to provide a table having a pedestal and a table

top. The pedestal 10 is of hollow construction and the table top 11 is provided with an opening 12 through which cooled air is delivered toward the occupants of the table.

The lower end of the member or pedestal 10 has a base 13 which provides a closure for this end of the structure and said member 10 is provided with a plurality of air inlet openings 19. The member 10 is preferably constructed of an inner shell 14 and an outer shell 15 the two being separated from each other through the medium of insulation 16, the latter being employed so as to reduce occurrence of condensation upon the outer surface of the member 10.

The cooling agent generally designated 17 is supported within the shell 14, it being located in spaced relation thereto so as to provide a circumferential air passage 18 with which the openings 19 communicate.

The cooling agent 17 in this construction is 20 comprised of an open ended chamber 20 which is adapted to receive cracked ice and produce means with which air circulated by the air advancing means 25 through the passage 18 may engage prior to its being discharged through 25 the opening 12 located adjacent the table top. This chamber 20 is provided with a cup 22 for catching condensate forming upon the outer portion of the chamber 20 and is further provided with supports such as 23 which cooperate with 30 supports 24 projecting from the inner face of the shell 14 to hold this chamber in proper relation to other elements of the device.

The chamber 20 is designed to be removably arranged within the member 10 and is provided 35 with a removable cover 26 so as to permit filling of the chamber with a cooling medium. This cover 26 is of a dimension so that when applied to the chamber 20 and the latter is located within the shell 14, the passage 12 is formed.

40 It will be noted that the closure 26 and the upper termination of the member generally designated 10 are formed with means respectively designated 27 and 28 so as to deflect the cooled air in a lateral direction relatively to the member 10, and deliver same at one side of the plane of the table top 11 and toward an occupant of the table.

The chamber 20 is provided with handles such as that designated 29 to facilitate handling during removal and insertion of said chamber to and from the support or member 10.

45 It is understood that the device is susceptible of use to merely cause circulation of air without cooling same when this is found necessary 55

or desirable, it being evident that the air advancing means will cause air to be circulated and discharged in the manner hereinabove referred to and that this may be accomplished merely by omitting the use of a cooling agent.

It is understood also that the cooling agent may be of any desired character and may consist of the ordinary cooling coils arranged within the pedestal or support 10 and may also be in 10 the form shown in Fig. 5 which contemplates the utilization of a container 30 which is secured to the member 31 and contains a block of ice 30' which is frozen in said container, the latter being designed to be supported within the member 10. 15 In the modification shown in Fig. 2, employment of air advancing means and also cooling means is contemplated. In this arrangement a chamber for a cooling medium is employed and designated 20', having a cover 26' detachably connected therewith, the chamber being adapted to be introduced to the member 10' through the opening 12' provided in the table top. The member 10' is provided with a plurality of apertures 32 and the table top 33 is also provided with 20 a series of apertures 34 with which the apertures 32 communicate. Air circulating from the apertures 32 is assisted in its circulation toward the apertures 34 by means of a circumferential baffle plate 46 which will direct the air in the manner just referred to. The table top 33 may have the underside thereof provided with insulation 33' to prevent the occurrence of moisture.

In the structure shown in Fig. 3, the table top 36 is of a hollow character, it being comprised 35 of the walls 37 and 38 which are spaced from each other to provide an air space 39. This air space 39 communicates with the air passage 40 which corresponds in function to the air passage 18 and may be formed in a manner similar 40 to said last mentioned passage. The space 39 is open at 41 so that air circulating through the space 39 and the passage 40 may be discharged from the openings 41 at an edge of the table top. Since the external formation of the table 45 top may be either of a circular or square character, it is manifest that by providing shutters such as those generally designated 42, the degree or amount of air directed toward a particular occupant of the table may be regulated according 50 to the desires of the occupant.

By referring to Fig. 3, it will be noted that an internally projecting flange 43 having a pin 44 is provided. This pin is adapted to cooperate with the bayonet slot 45 provided in the member 55 such as 31 shown in Fig. 5 to removably hold the member shown in Fig. 5 relative to other portions of the table structure.

In Fig. 4, the table top 48 is of hollow formation as is the support or pedestal 49 and the latter is provided with a series of air outlet openings 50 which are located below the lower wall 51 of the table top to thus permit the lower wall 51 to function as a deflector for deflecting air along the lower portion of the table top to the periphery of the table top. A baffle 51' is located below the openings 50 to direct air toward the table top 48.

From the foregoing description, it is evident that a combination of elements is provided which 70 combine to provide a piece of furniture such as a table having means for circulating air and directing the air toward the occupants of the table. In addition thereto, it is evident that the structure may also include a cooling agent located in 75 the path of the air currents set up by the air

advancing means 25 and therefore said air may be cooled prior to its discharge from the device and be directed toward the occupants of the table. In addition, it is manifest that the structure involves means for regulating the amount or degree of air circulating from the device and that this means may be operated by any one of several occupants of the table so as to regulate the amount of air directed toward a particular individual at said table.

Having thus described the invention, what I claim as new and desire to cover by Letters Patent is:

1. An article of furniture comprising a tubular pedestal having an outlet adjacent its upper end and inlet openings near its lower end and means near its upper end for removably supporting a cooling element in spaced relation to the walls of said pedestal in combination with a transverse member mounted at the upper end 15 of said pedestal with its margins extending beyond the sides thereof, means for directing air from said outlet toward the margins of said member and adjacent the plane thereof, and means for producing a current of air through 20 said pedestal.

2. An article of furniture comprising a tubular pedestal having an outlet adjacent its upper end and inlet openings near its lower end and means near its upper end for removably supporting a 30 cooling element in spaced relation to the walls of said pedestal in combination with a transverse member mounted at the upper end of said pedestal with its margins extending beyond the sides thereof and provided with an opening there- 35 through for removing said cooling element from said pedestal, means for directing air from said outlet toward the margins of said member and adjacent the plane thereof, and means for producing a current of air through 40 said pedestal.

3. An article of furniture comprising a tubular pedestal having an outlet at its upper end and inlet openings near its lower end and means near its upper end for supporting a cooling element in spaced relation to the walls of said pedestal 45 in combination with a transverse member mounted at the upper end of said pedestal with its margins extending beyond the walls thereof, means removably mounted upon said cooling element for partially closing said outlet and co- 50 operating with means upon the pedestal for di- recting air from said outlet toward the margins of said member and adjacent the plane thereof, and means for producing a current of air through 55 said pedestal.

4. An article of furniture comprising a tubular pedestal having an outlet at its upper end and inlet openings near its lower end and means near its upper end for removably supporting a cooling element in spaced relation to the walls 60 of said pedestal in combination with a trans- 65 verse member mounted at the upper end of said pedestal with its margins extending beyond the sides thereof and provided with an opening there- through for removing said cooling element from said pedestal, means removably mounted upon said cooling element for partially closing said outlet and cooperating with means upon the pedestal for directing air from said outlet toward the margins of said member, and means for 70 producing a current of air through said pedestal.

5. An article of furniture comprising a tubular pedestal having an outlet at its upper end and inlet openings near its lower end and means near its upper end for supporting a cooling element 75

- in spaced relation to the walls of said pedestal in combination with a transverse member mounted at the upper end of said pedestal, its margins extending beyond the sides thereof, means for 5 directing air from said outlet toward the margins of said member, means near said margins for controlling the air from said outlet at said margins, and means for producing a current of air through said pedestal.
10. An article of furniture comprising a tubular pedestal having an outlet at its upper end and inlet openings near its lower end, a cooling element adapted to loosely fit within said pedestal comprising a fluid tight receptacle adapted to contain a cooling medium, said cooling element having means at its upper end arranged to cooperate with means connected to the pedestal for supporting said cooling element in position with its walls in spaced relation to the walls of the 10 pedestal in combination with a transverse member mounted at the upper end of said pedestal with its margins extending beyond the sides thereof, means for directing air from said outlet toward the margins of said member, and means 15 for producing a current of air through said pedestal. 5
15. An article of furniture comprising a tubular pedestal having an outlet adjacent its upper end and inlet openings near its lower end, and means near its upper end for supporting a cooling element in spaced relation to the walls of said pedestal in combination with a transverse member mounted at the upper end of said pedestal with its margins extending beyond the sides thereof, means for directing air from said outlet toward the margins of the member and adjacent the 20 plane thereof, and means within the pedestal above said inlet openings for producing a current of air through said pedestal. 15
20. An article of furniture comprising a tubular pedestal having an outlet at its upper end and inlet openings near its lower end, and means near its upper end for removably supporting a cooling element in spaced relation to the walls of said pedestal in combination with a transverse member mounted at the upper end of said pedestal with its margins extending beyond the sides thereof and provided with an opening therethrough for removing said cooling element from said pedestal, means for directing air from said outlet toward the margins of said member, and 30 means within the pedestal for producing a current of air through said pedestal. 25
25. An article of furniture comprising a tubular pedestal having an outlet at its upper end and inlet openings near its lower end, and means near its upper end for removably supporting a cooling element in spaced relation to the walls of said pedestal in combination with a transverse member mounted at the upper end of said pedestal with its margins extending beyond the sides thereof and provided with an opening therethrough for removing said cooling element from said pedestal, means removably mounted upon said cooling element for partially closing said outlet and cooperating with means upon the 35 pedestal for directing air from said outlet toward the margins of said member and adjacent the plane thereof, and means near said margin for controlling the air from said outlet at said margin, and means for producing a current of air through said pedestal. 35
40. An article of furniture comprising a tubular pedestal having an outlet at its upper end and inlet openings near its lower end, and means near its upper end for removably supporting a cooling element in spaced relation to the walls of said pedestal in combination with a transverse member mounted at the upper end of said pedestal with its margins extending beyond the sides thereof and provided with an opening therethrough for removing said cooling element from said pedestal, means removably mounted upon said cooling element for partially closing said outlet and cooperating with means upon the 45 pedestal for directing air from said outlet toward the margins of said member and adjacent the plane thereof, and means near said margin for controlling the air from said outlet at said margin, and means for producing a current of air through said pedestal. 40
45. An article of furniture comprising a tubular pedestal having an outlet at its upper end and inlet openings near its lower end, a cooling element adapted to loosely fit within said pedestal comprising a fluid tight receptacle adapted to contain a cooling medium and having means adapted to cooperate with means connected to said pedestal to removably lock the same in position with its walls in spaced relation to the 50 walls of said pedestal in combination with a transverse member mounted at the upper end of said pedestal with its margins extending beyond the sides thereof and provided with an opening therethrough for removing said cooling element from said pedestal, means for directing air from said outlet in a direction substantially parallel to the plane of said member and toward the margins thereof, and means between the bottom of said cooling element and said inlet openings for producing a current of air through said pedestal. 55
50. An article of furniture comprising a tubular pedestal having an outlet at its upper end and inlet openings near its lower end, and means near its upper end for removably supporting a cooling element in spaced relation to the walls of said pedestal in combination with a transverse member mounted at the upper end of said pedestal with its margins extending beyond the sides thereof and provided with an opening therethrough for removing said cooling element from said pedestal, means for directing air from said outlet toward the margins of said member, means near 55 said margin for controlling the air from said outlet at said margin, and means within the pedestal, below said cooling element but above said inlet openings, for producing a current of air through said pedestal. 70
55. An article of furniture comprising a tubular pedestal having an outlet adjacent its upper end and inlet openings near its lower end and means near its upper end for supporting a cooling element in spaced relation to the walls of said pedestal in combination with a transverse member mounted at the upper end of said pedestal, the margins of said member extending beyond the sides of the pedestal and having openings formed in said margins, means for directing air from said outlet toward the openings formed in the margins of said member, and means for producing a current of air through said pedestal. 60
60. An article of furniture comprising a tubular pedestal having an outlet at its upper end and inlet openings near its lower end, and means near its upper end for supporting a cooling element in spaced relation to the walls of said pedestal in combination with a transverse member mounted at the upper end of said pedestal, the margins of said member extending beyond the sides of the pedestal and having openings formed in said margins, means for directing air from said outlet toward the openings formed in the margins of said member, and means for producing a current of air through said pedestal. 65
65. An article of furniture comprising a tubular pedestal having an outlet adjacent its upper end and inlet openings near its lower end and means near its upper end for supporting a cooling element in spaced relation to the walls of said pedestal in combination with a transverse member mounted at the upper end of said pedestal, the margins of said member extending beyond the sides of the pedestal and having openings formed in said margins, means for directing air from said outlet toward the openings formed in the margins of said member, and means for producing a current of air through said pedestal. 70
